BIN CONSTRUCTION

Rodney D. Jacobson, Ray, N. Dak., assignor to Jacobson
& Son Construction Company, Inc., Ray, N. Dak.,
a corporation of North Dakota

Filed Oct. 16, 1968, Ser. No. 14,010

Term of patent 14 years

Int. Cl. D25—04

U.S. Cl. D13—1

FIG. 1

FIG. 2

FIG. 3

FIG. 4

FIG. 5

FIG. 6

FIG. 1 is a view in side elevation of a bin construction showing my new design, the side opposite that shown being substantially a mirror image;

FIG. 2 is a view in bottom plan thereof;

FIG. 3 is a view of top plan thereof;

FIG. 4 is a view in end elevation thereof, the end opposite that shown being substantially a mirror image;

FIG. 5 is an enlarged view in perspective thereof, as seen from one end and above; and

FIG. 6 is a view in perspective similar to FIG. 5 as seen from below.

I claim:

The ornamental design for a bin construction, substantially as shown and described.
